UNITED STATES PATENT OFFICE.

JOSEPH H. CHAMP, OF CLEVELAND, OHIO.

BOTTLE-CENTERING DEVICE FOR BOTTLE-FILLING MACHINES.

No. 909,668.

Specification of Letters Patent.

Patented Jan. 19, 1909.

Application filed October 26, 1906. Serial No. 340,647.

To all whom it may concern:

Be it known that I, JOSEPH H. CHAMP, a citizen of the United States, resident of Cleveland, county of Cuyahoga, and State of Ohio, have invented a new and useful Improvement in Bottle-Centering Devices for Bottle-Filling Machines, of which the following is a specification, the principle of the invention being herein explained and the best mode in which I have contemplated applying that principle, so as to distinguish it from other inventions.

My present invention relates to bottle filling machines, particularly to machines intended for the automatic filling of bottles with beer or like liquids under pressure. In approved machines of this sort there is generally provided a bottle filling member including a suitable mouth piece and discharge tube against which the bottle is designed to be raised and held pending the filling operation. Inasmuch as the automatic operation of the machine includes, among other things, the raising of the bottle into position with respect to such mouth piece and discharge tube, it is quite essential that such bottle be accurately centered in order that its registry with the mouth piece and discharge tube may be correct.

This invention, then, has regard more particularly still to means adapted to effect such last noted essential result.

Said invention consists of the means hereinafter described and particularly pointed out in the claims.

The annexed drawings and the following description set forth in detail certain mechanism embodying the invention, such disclosed means constituting but one of various mechanical forms in which the principle of the invention may be used.

In said annexed drawings, Figure 1 is a front perspective view of so much of an approved type of bottle filling machine as is directly connected with the handling and filling of bottles, with my said invention shown as incorporated therein and adapted to operate in conjunction therewith; Fig. 2 represents the same parts as shown in Fig. 1 in the position assumed by them at a different stage in their operation; Fig. 3 is a side elevation of such parts in the position corresponding to that shown in Fig. 2, such parts, however, being arranged to accommodate bottles of a different size; Fig. 4 is a broken side elevation of the same parts

shown in Fig. 3, but in a position corresponding to that shown in Fig. 1, and viewed in the opposite direction from that in which they appear in said Fig. 3; and Fig. 5 is a transverse cross section of a structural detail entering into my invention.

As has been indicated, I have chosen for the purpose of illustrating the manner of operation of my bottle centering device one form of bottle filling machine. I do not mean, however, by this to imply that such device is limited in its application to this single form of machine; on the contrary, as will be readily apparent from the following description, such device is adapted in general to be used with machines characterized by having a filling member to which the bottle is mechanically approached. As has been further stated, only such parts of the machine in question are here illustrated as are directly concerned with the operation of present interest. Taking up, then, the consideration of these parts, it will be noted first of all, from an inspection of the several figures, that they comprise two relatively fixed members, an arm A leading from the beer tank or other source of supply and a horizontal bearing bar A', whereby the other parts of the mechanism are supported as will appear. The central structure or machine frame, from which such arm and bar project, is omitted for the reasons already set forth and it is furthermore immaterial whether or not such structure has a movement of its own, as for example one of rotation about a pivotal axis. The particular structure here illustrated is supposed to have such movement but while certain operations of the filling mechanism are functional with respect to this movement, the latter has no direct operative connection with the bottle centering device.

Arm A, of which the outer portion a alone appears, is provided with appropriate fluid-ways leading from the central supply chamber for conducting the beer therefrom to the bottle filling member C, as also a suitable actuating fluid, as compressed air, from a chamber associated with the central beer tank to such member and to certain other parts of the mechanism designed to be operated by such fluid. Such outer end a is formed with a suitable valve seat for the reception of a plug valve B whereby communication may be controlled between the respective fluid-ways in arm A and bottle

filling member or mouth piece C, and such other parts of the mechanism. The details of the construction whereby communication is thus controlled have been omitted as being immaterial so far as the operation of my centering device is concerned. Actuation of valve plug B is effected by the rocking of a tripping device D fastened to its outer end and so designed that such valve and its said 10 tripping device must necessarily turn together in all horizontal rocking movements about the longitudinal axis of the valve. Actuation of tripping device D is designed to be automatically effected at proper times 15 in the particular machine here represented by engagement of its respective arms d d' with suitable stops disposed in its path of movement as the machine frame rotates. Since usually in machines of the character 20 here shown, the bottle supporting member has definitely limited movements, it becomes necessary, in order to adapt the machine for use with bottles of different sizes, to supply a supplemental mouth piece C' in order that 25 suitable connection with the filling member may be effected by the mouth of a bottle below the maximum size. Thus such supplemental mouth piece is shown in Figs. 1 and 2 where the bottles illustrated are pints, 30 while with the quart bottles appearing in Figs. 3 and 4, this element is omitted. Supplemental mouth piece C' is fitted directly upon mouth piece C, being retained in place by means of outwardly projecting spring 35 clamps e which embrace the side wall of said upper mouth piece C and maintain said lower mouth piece fitted in close connection with said upper mouth piece. Such upper mouth piece C is provided with a depending 40 discharge tube c' that is designed, when the supplemental mouth piece C' is employed, to project through a suitable aperture therein, such lower mouth piece being provided with a short depending tube c² that incloses 45 tube c' and is formed with lateral openings whereby communication may be had with the interior of the respective mouth pieces and thence with certain of the fluid-ways in arm A, in addition to the connection afforded through tube c' which is designed 50 to convey from the supply tank the beer wherewith the bottles are to be filled.

Supported between fluid-way arm A and horizontal bearing bar A', and extending a short distance below the latter, are two vertically disposed, axially aligned cylinders E E' in which is reciprocably mounted the piston E². Reciprocation of piston E² is automatically effected at desired intervals 55 by the introduction on the proper sides of the piston head of the actuating fluid to which reference has already been made, introduction of such fluid being controlled by the same valve B that controls the admission 60 of the beer to the bottles. On the

lower end of piston E² is adjustably mounted a bracket e, and in a sleeve e¹⁰ on the outer end of this bracket is adjustably mounted the stem F of the bottle rest F' on which a bottle is designed to be placed pending the filling operation. Such bottle rest F' is preferably formed on stem F so that its upper surface will lie at another than a right angle to such stem in order to assist in placing in proper position thereon bottles 75 having uneven bottoms. To prevent the bottle from sliding off the rest, the latter is formed with an up-turned peripheral flange f' partially inclosing its upper face. In addition to this flange on its upper side the 80 rest has its under side provided with two depending lips f², respectively located free from and to opposite sides of stem F, in the line of horizontal travel of bar A'; such lips having a horizontal space between them 85 equal to the width of horizontal bar A', and adapted to have lateral bearing respectively against the front and rear edges of said bar.

The operation of the mechanism thus far described should be readily apparent. The 90 bottle is placed upon rest F' when in its lower position corresponding with the extended position of piston E² that is shown in Figs. 1 and 4. By rotating the bottle it can be caused to assume an approximately 95 vertical position upon such rest, even though its bottom be uneven, by virtue of the described construction to such rest. The rest is designed to be thereupon vertically raised until the mouth of the bottle 100 is pressed tightly against mouth piece C or C', depending on the size of the bottle being filled. This movement of the rest is effected by introduction of the compressed fluid used to actuate a piston E² into the 105 proper chamber in cylinders E E', such introduction being controlled, as before stated, by valve plug B. The rest F', upon the bottle being filled, is again lowered to its original position whereupon such filled bottle 110 is replaced by an empty one and the operation repeated.

Inasmuch as the operations described, including the action of valve plug B are entirely automatic, it is quite essential that 115 the bottle as placed on bottle rest F' be centered so as to properly engage depending discharge tube c' and mouth piece C or C'. It has heretofore been sought to accomplish this result by providing a rest for the neck 120 of the bottle in connection with such rest F'. This method however, has been found objectionable since the bottles even when of the same size are apt to be of a more or less irregular form and since further, by virtue 125 of the very means employed to secure their vertical position on the rest their mouths are apt to be displaced out of proper alignment with depending tube c'. It is to correct these several difficulties that the mech- 130

anism which I shall now proceed to describe has been devised.

Intermediately of fluid-way arm A and horizontal bearing bar A', is pivotally mounted with respect to the frame, of which such arm and bar are component parts, a lever arm H. Specifically I thus attach such arm to another arm H² that is securely but adjustably clamped to upper piston E by means of a clamp collar h. The longer, forwardly projecting, portion of lever H is formed with a guide-plate having a concave face disposed in one position of said arm to lie obliquely across the path of travel of bottle rest F'. The upper end of such guide-plate H' when thus forwardly inclined extends into close proximity with the lower end of depending discharge tube e' and is in fact formed with a deep notch h³ within which such tube end is designed to lie when thus obliquely disposed, Figs. 1 and 4. In this position guide-plate E' will engage the neck of a bottle borne on bottle rest G' irrespective of any possible variation in its location in such rest or of any unusual inclination from the normal vertical position that it may assume; and by virtue of the conformation of its concave surface it will direct the mouth of such bottle without fail into engagement with the lower end of discharge tube e'. The pivotal axis of arm H, whereby such guide-plate H' is borne, is located laterally of the path of travel of the bottle and so disposed that the engagement of the body of the bottle, and later on of the rest F' upon which said bottle stands, with the guide-plate in question will deflect said plate entirely out of the path of such rest. This is the position that it is shown as occupying in Figs. 2 and 3.

The mounting of arm H is designed, in addition to permitting the movement just described, to frictionally retain such arm in whatever position it may be placed. The detail in Fig. 5, illustrates one approved means for securing this result. As there appears the arm is mounted upon a boss h¹¹, being secured thereon by means of a set screw h⁶ and washer h⁷; a helical spring h⁸ interposed between the arm and the head of such set screw by appropriate adjustment of set screw h⁶ is adapted to produce the proper degree of pressure between the bearing face of arm H, which face is preferably of annular formation as shown, with the opposed surface of arm H². The guide-plate H', it is thus seen will remain in the position assumed by it upon being thrust aside by bottle rest F' as the latter moves upwardly, not only during its positive retention thereby the latter while in its upper position but also pending the return of the rest to its normal lower position. However, I provide means for returning guide-plate H' into its forwardly projecting active position, upon the

completion of such return movement of bottle rest F' in order that the plate may engage and properly guide the next bottle when the rest is again raised. The means, whereby such positioning of the guide-plate is effected comprise a rocker H³ loosely resting on the upper face of bearing bar A' and held against displacement therefrom by means of downwardly extending lips h⁵ which engage the lateral edges of the bar much as do those f² of bottle rest F. Such rocker is formed on its under side with two flat longitudinally disposed faces inclined to each other at a suitable angle, and is operatively connected with guide-plate bearing lever H by means of a member of adjustable length comprising a sleeve h³ that loosely rests in a depression in the rear end of such rocker, and a rod h' adjustably held in such sleeve at its lower end by means of a set screw, and having its upper end slidably held in a sleeve h⁴ in the extreme end of fixed arm H² and thereabove pivotally attached to the rear and shorter arm of lever H. The forward end of rocker H³ extends into the path of bottle rest F' and is adapted to be engaged and depressed thereby as the latter resumes its normal lower position, thus raising the rear end of the rocker and actuating lever H to actively position guide-plate H' as above described. The raising of the rest with a bottle thereon, by deflecting the plate H', depresses in turn the rear end of rocker H³ as will be evident, in which position the parts in question remain owing to the friction produced at the bearing of lever H by spring h⁸.

By appropriately forming the concave face of guide-plate H' it will be evident that my bottle centering device may be adapted to handle bottles of any conformation, or size, that the bottle filling machine is otherwise capable of handling. The means entering into the construction of such bottle centering or guiding device, are not limited in their connection with bottle filling mechanism to mechanism of the particular type here chosen for the purpose of illustration, but may be employed with equal facility and like satisfactory results in any bottle filling machine in which the bottles are brought into register with the filling member, irrespective of the manner in which the filling is actually accomplished or of the manner in which the registering of the bottle is effected. They can also, as will be readily apparent, be adapted to handle vessels other than bottles, where such vessels are of a similar character and require to be approached to an operating mechanism more or less strictly in alignment therewith. Accordingly, wherever the term bottle appears in the foregoing description or the following claims, the same should be understood as including any suitable vessel. And as has

already been indicated, wherever the term beer appears in the foregoing description or the following claims the same should be understood as including any suitable fluid.

5. Other modes of applying the principle of my invention may be employed instead of the one explained, change being made as regards the mechanism herein disclosed providing the means stated by any one of the 10 following claims or the equivalent of such stated means, be employed:

I would therefore particularly point out and distinctly claim as my invention:—

1. The combination with a bottle-filling member; of a movable guide-member adapted in one position to engage a bottle and center the same with respect to said filling-member and in another position to lie without the path of movement of such 20 bottle; and means adapted to retain said guide-member in whatever position it may be placed.

2. The combination with a bottle-filling member and a movable bottle support adapted to approach a bottle thereto; of a movable guide member adapted in one position to engage a bottle upon said support incidentally to the movement of the latter, so as to direct the mouth of such bottle into 30 register with said filling-member, and in another position to lie without the path of movement of such bottle, and means adapted frictionally to hold said guide member in whatever position it may be placed.

3. The combination with a bottle-filling member and a movable bottle support adapted to approach a bottle thereto; of a movable guide member normally frictionally held in position to engage a bottle upon said support incidentally to its movement by the latter, said guide member being adapted to direct the mouth of such bottle into register with said filling member and to be itself deflected by said support.

4. The combination with a bottle-filling member and a movable bottle support adapted to approach a bottle thereto; a movable plate pivotally mounted laterally of the path of movement of said support and having a concave deflecting face, said plate being adapted in one position to present such face obliquely to a bottle on said bottle support pending the movement of the latter, so as to direct the mouth of such bottle into 55 register with said filling member and in another position to lie without the path of movement of such bottle and said support.

5. The combination with a bottle-filling member and a movable bottle support adapted to approach a bottle thereto; of a movable plate pivotally mounted laterally of the path of movement of said support and having a concave deflecting face, said plate being normally frictionally held to 65 present such face obliquely to a bottle on

said bottle support pending the movement of the latter, so as to direct the mouth of such bottle into register with said filling member, and being movable from such position by engagement with the body of such 70 bottle.

6. The combination with a mouth piece provided with a depending discharge tube, and a vertically reciprocable bottle support adapted to approach a bottle to said mouth 75 piece; of a plate pivotally mounted laterally of the path of movement of said support and having a concave deflecting face, said plate being normally frictionally held to present such face obliquely to a bottle on 80 said bottle support pending the upward movement of the latter, so as to direct the mouth of such bottle into register with said discharge tube and being movable from such position by engagement with the body 85 of such bottle.

7. The combination with a mouth piece provided with a depending discharge tube, and a vertically reciprocable bottle support adapted to approach a bottle to said mouth 90 piece; of an oscillatorily mounted plate having a concave deflecting face notched at its upper end, said plate being adapted in one position to present such face obliquely to a bottle on said bottle support pending the 95 upward movement of the latter and to receive said depending discharge tube in its upper notched end, whereby the mouth of such bottle is directed into register with said discharge tube, and being adapted in 100 another position to lie without the path of movement of such bottle and said support.

8. The combination with relatively movable bottle-filling and supporting means; of movable, frictionally held, bottle-guiding 105 means connected to be positively positioned by such relative movement of the bottle-filling and supporting means.

9. The combination with a movable bottle support, of movable, frictionally held bottle-guiding means adapted to be positively positioned by said support.

10. The combination with a movable bottle support, of movable bottle-guiding means, means for positioning said bottle-guiding 110 means, said positioning means being operatively engaged by said support during a part only of the latter's movement, and means for frictionally retaining said bottle-guiding means in whatever position they 120 may be placed.

11. The combination with a bottle-filling member and a movable bottle support adapted to approach a bottle to said filling member, of means adapted in one position to engage the bottle incidentally to the movement of said support and to center the same with respect to said filling member, the positioning of said means being positively effected by movement of said support.

12. The combination with a mouth piece provided with a depending discharge tube, and a vertically reciprocable bottle support adapted to approach a bottle to said mouth piece; of a movable guide member normally frictionally held in position to engage a bottle upon said support pending the upward movement of the latter, said guide member being adapted to direct the mouth 5 of such bottle into register with said discharge tube and to be thereupon deflected by said bottle support; and means adapted to be positively actuated by said support upon the downward movement thereof, to 10 return said guide member to its normal position.
13. The combination with a mouth-piece provided with a depending discharge tube, and a vertically reciprocable bottle support 20 adapted to approach a bottle to said mouth-piece; of a movable guide member normally frictionally held in position to engage a bottle upon said support pending the upward movement of the latter, said guide 25 member being adapted to direct the mouth of said bottle into register with said discharge tube and to be thereupon deflected by said bottle support; and means adapted to be positively actuated by said support, as 30 the latter approaches its lower limit of movement, to return said guide member to its normal position.
14. The combination with a bottle filling member and a movable bottle support adapted to approach a bottle to said filling member; of an oscillatorily mounted guide plate adapted in one position to lie obliquely across the path of travel of said support and to be deflected from such path thereby; and 40 means adapted to be actuated by said support to return said plate to its first position.
15. The combination with a bottle filling member and a movable bottle support adapted to approach a bottle to said filling member; of an oscillatorily mounted guide plate having a concave face disposed in one position of said plate to lie obliquely across the path of travel of said support and to be deflected from such path thereby; and means 45 adapted to be actuated by said support upon the downward movement thereof to return said plate to its first position.
16. The combination with a bottle filling member and a movable bottle support adapted to approach a bottle to said filling member; of a movable guide member adapted in one position to direct the mouth of a bottle borne by said support with respect to said filling member and thereupon to be 55 deflected from such position by the body of such bottle, said guide member being adapted to remain in whatever position it may be placed.
17. The combination with a bottle filling member and a movable bottle support 60 adapted to approach a bottle to said filling member; of a movable guide member adapted in one position to direct the mouth of a bottle borne by said support with respect to said filling member; and adjustable means frictionally holding said guide member in whatever position it may be placed.
18. The combination with a bottle filling member and a movable bottle support 70 adapted to approach a bottle to said filling member; of a movable guide member adapted to direct a bottle borne by said support with respect to said filling member, said guide member being adapted to remain in 75 whatever position it may be placed; and means adapted to be positively actuated by said support upon the movement thereof in one direction to operatively position said guide member, said support being adapted 80 upon its reverse movement to deflect said member into its inoperative position.
19. The combination with a bottle-filling member and a movable bottle support adapted to approach a bottle to said filling member; of a movable guide member adapted to direct a bottle borne by said support with respect to said filling member, said guide member being adapted to remain in 90 whatever position it may be placed; and means adapted to be positively actuated by said support, as the latter approaches its lower limit of movement, to position said guide member, said support being adapted 95 upon its reverse movement to deflect said member into its inoperative position.
20. The combination with a bottle filling member and a movable bottle support adapted to approach a bottle thereto; of a movable guide member adapted to direct a bottle 100 borne by said support with respect to said filling member; and adjustable means frictionally holding said guide member in whatever position it may be placed.
21. The combination with a suitable 110 frame; of a relatively fixed bottle filling member; a movable bottle support adapted to approach a bottle to said filling member; an arm pivotally attached to said frame and having an annular bearing surface at the 115 point of such pivotal attachment; means resiliently pressing said surface against the opposed surface in said frame; and a guide plate borne by said arm and adapted in one position of the latter to lie obliquely across 120 the path of travel of said support and to be deflected from such path thereby.
22. The combination with a suitable frame; of a relatively fixed bottle filling member; a movable bottle support adapted 125 to approach a bottle to said filling member; an arm pivotally attached to said frame and adapted to be retained in whatever position it may be placed; a guide plate borne by said arm and adapted in the normal posi- 130

tion of the latter to lie obliquely across the path of travel of said support and to be deflected from such path thereby; and a rocker mounted in said frame and operatively connected with said arm, said rocker being positioned to be engaged and actuated by said support upon its return movement.

23. The combination with a suitable frame; of a relatively fixed mouth piece, 10 provided with a depending discharge tube; a vertically reciprocable bottle support adapted to approach a bottle to said mouth piece; an arm pivotally attached to said frame and adapted to be frictionally held 15 in whatever position it may be placed; a guide plate borne by said arm and adapted

in the normal position of the latter to lie obliquely across the path of travel of said support and to be deflected from such path thereby; a rocker mounted in said frame; 20 and adjustable means connecting said rocker with said arm to restore the latter to its normal position, said rocker being positioned to be engaged and actuated by said support upon its return movement.

Signed by me, this 23rd day of October, 1906.

JOSEPH H. CHAMP.
